UNITED STATES PATENT OFFICE.

FRANK G. STIMSON, OF HAMDEN, CONNECTICUT, ASSIGNOR TO WINCHESTER REPEATING ARMS COMPANY, OF NEW HAVEN, CONNECTICUT, A CORPORATION OF CONNECTICUT.

DESIGN FOR A BATTERY HANDLAMP.

Application filed June 14, 1922. Serial No. 2,688. Term of patent 14 years.

To all whom it may concern:

Be it known that I, FRANK G. STIMSON, a citizen of the United States, residing at Hamden, Connecticut, have invented a new, original, and ornamental Design for a Battery Handlamp, of which the following is a specification, reference being had to the accompanying drawing, forming part thereof.

Figure 1 is a side view;
Figure 2 is an end view, and
Figure 3 is a view in perspective of a battery hand lamp showing my new design.

I claim:

The ornamental design for a battery handlamp as shown.

FRANK G. STIMSON.
